MICROWAVE OVEN

George W. Meissner, Fridley, and William E. Stumpf,
Excelsior, Minn., assignors, by mesne assignments, to
Litton Precision Products, Inc., Beverly Hills, Calif., a
corporation of Delaware

Filed Apr. 20, 1964, Ser. No. 79,589

Term of patent 14 years

(Cl. D16—2)

FIG. 1

FIG. 2

FIG. 3

FIG. 4

FIGURE 1 is a perspective view of a microwave oven, embodying our novel design;

FIGURE 2 is a front elevation view of the microwave oven shown in FIGURE 1;

FIGURE 3 is a top view of the microwave oven shown in FIGURE 1; and

FIGURE 4 is a side elevational view of the microwave oven shown in FIGURE 1.

We claim:

The ornamental design for a microwave oven, substantially as shown.
